UNITED STATES PATENT OFFICE.

HORACE L. RILEY, OF RICHWOOD, WEST VIRGINIA.

COMPRESSED-AIR WATER-ELEVATOR.

1,121,402.

Specification of Letters Patent. Patented Dec. 15, 1914.

Application filed April 7, 1914. Serial No. 830,236.

To all whom it may concern:

Be it known that I, HORACE L. RILEY, a citizen of the United States, residing at Richwood, in the county of Nicholas and State of West Virginia, have invented new and useful Improvements in Compressed-Air Water-Elevators, of which the following is a specification.

This invention is an improved apparatus 10 for elevating water or other liquid by means of fluid under pressure, such for instance as compressed air, the apparatus being especially adapted for use in driven or bored wells for raising water therefrom by means 15 of compressed air, the object of the invention being to provide an improved apparatus of this character which is cheap and simple, is not likely to get out of order and which insures the delivery of a proper proportion 20 of compressed air with the column of water and is substantially automatic in operation, so that as long as compressed air is supplied to the apparatus and there is a supply of water, the latter will be raised 25 and delivered at the mouth of the well.

The invention consists in the construction, combination and arrangement of devices hereinafter described and claimed.

In the accompanying drawings:—Figure 30 1 is a vertical sectional view of a portion of a well casing provided with compressed air water elevating apparatus constructed in accordance with my invention and showing such apparatus partly in elevation and 35 partly in section. Fig. 2 is a horizontal sectional view of the same on a plane intersecting the horizontal part of the air supply pipe. Fig. 3 is a vertical central sectional view of the same. Fig. 4 is a detail sectional view on a plane intersecting the upper portion of the eduction pipe. Fig. 5 is a 40 similar view on a plane intersecting the lower portion of the eduction pipe and also intersecting the cage. Fig. 6 is an enlarged detail sectional view of the return 45 air jet nozzle.

A tubular well casing is indicated at 1 and is provided at its upper end with a collar 2 which is threaded thereto and forms 50 an outstanding annular flange. A nipple 3 is arranged at the upper end of and with its lower portion in the well casing 1 and is provided with a collar 4 which is threaded thereon and which forms a cap for the upper end of the well casing. A packing 55 gasket 5 is interposed between the collars

2 and 4 and said collars are secured together by clamping bolts 6. The nipple is also provided with a locking nut 7 which bears on the collar 4. 60

An eduction pipe 8 is connected to the lower end of the nipple 3 by a coupling 9. The eduction pipe is of suitable length, extends down in the well casing to a point below the level of the water in the well and 65 the said eduction pipe is provided at a point near its lower, submerged end with vertically elongated intake openings 10 for water. An air jet cage 11 is arranged in and removable from the lower portion of 70 the eduction pipe and is provided with a series of radial wings 12 which serve to divide that portion of the eduction pipe around the said cage into vertical channels each of which communicates with one of the 75 intake openings 10, the wings of the cage being arranged between said intake openings as shown. The said cage is cross-shaped in cross section and its upper end is provided with an inverted conical seat 13. 80 A closure nut 14 is screwed to the lower end of the eduction pipe and supports the cage and holds the latter in place.

The lower end of the vertical arm 15 of a T 16 is threaded to the upper end of the 85 nipple 3 and a water delivery pipe 17 is threaded to the upper end of said vertical arm of the T and may run to any point where it is desired to deliver water. In the horizontal arm 18 of the T is threaded a 90 plug 19. An air supply pipe 20 extends through the plug 19 and also extends down through the nipple 3 and the eduction pipe and is provided at its lower end with an upwardly directed air jet nozzle 21. A 95 packing gland 22 is threaded on the outer end of the plug 19 and the said air supply pipe also passes through said packing gland.

Any suitable means, such for instance as 100 a pump 23 may be employed for compressing air and supplying the same to my water elevating apparatus through the pipe 20.

The air jet nozzle 21 comprises an upper cone 24 which is threaded directly to the 105 lower end of the air supply pipe 20 and a lower cone 25 which is secured in spaced relation to the upper cone by means of spaced pins or rivets 26 and whereby an annular upwardly and outwardly directed jet opening 27 is formed between the said cones. 110

The operation of my invention is as fol-

lows:—When compressed air is forced through the pipe 20 it is discharged from the lower end thereof upwardly and outwardly by its jet nozzle 21 in that portion 5 of the eduction pipe immediately above the cage 11. This portion of the eduction pipe being below the level of water in the well the upwardly directed current of compressed air in passing upwardly through the 10 eduction pipe and delivery pipe serves to aerate the water and also to elevate the same so that a continuous stream of water is delivered between the delivery pipe as long as there is a supply in the well and compressed 15 air is kept supplied to the apparatus.

The cage, by reason of its cross sectionally cross shaped formation and the channels which it provides between the wings serves to control the supply of water to the 20 eduction pipe and to evenly distribute the water supply around the jet nozzle.

Having thus described my invention, I claim:—

1. A compressed air water elevator comprising a well casing, an eduction pipe arranged therein and provided with intake openings near its lower end, an air supply pipe extending downwardly in the eduction pipe and an upwardly and outwardly directed air jet nozzle at the lower end of the air supply pipe and arranged in the educ-

tion pipe at a point above the intake openings of the latter and a cage arranged in the lower portion of said eduction pipe, said cage comprising a series of vertically arranged wings arranged between the intake openings and forming channels in the lower portion of the eduction pipe. 35

2. A compressed air water elevator comprising a well casing, an eduction pipe arranged therein and provided with intake openings near its lower end, an air supply pipe extending downwardly in the eduction pipe and an upwardly and outwardly directed air jet nozzle at the lower end of the air supply pipe and arranged in the eduction pipe at a point above the intake openings of the latter and a cage arranged in the lower portion of said eduction pipe, said cage comprising a series of vertically 40 arranged wings arranged between the intake openings and forming channels in the lower portion of the eduction pipe, said cage having a seat at its upper end for the air jet nozzle and the eduction pipe being 45 provided with a closure nut at its lower end.

In testimony whereof I affix my signature in presence of two witnesses.

HORACE L. RILEY.
